HEAT EXCHANGER

John A. Gibb, New Rochelle, N. Y., assignor to
The Lummus Company, New York, N. Y., a cor-
poration of Delaware

Application September 14, 1939, Serial No. 294,797

4 Claims. (Cl. 257—225)

This invention relates to securing devices for detachably securing cover plates to vessels, and more particularly to floating head cover sealing devices for tubular type heat exchangers having a tube bundle within a shell.

In heat exchange construction of the shell and tube type, it is the practice to provide a cover or channel for the floating or movable tube sheet by which the fluid within the tubes is transferred from one part of the tube bank to another. It is also known that the floating tube sheets are preferably made sufficiently small in diameter so the tube bundle can be withdrawn from the shell. My present invention relates to the manner by which the cover is secured to the tube sheet so that the cover and the securing means can be removed from the tube sheet in such a manner that the tube sheet can be withdrawn through the shell.

The principal object of the present invention is to provide a simplified securing means by which a cover can be secured to the floating tube sheet of a heat exchanger with adequate provision against loss of sealing pressure, irrespective of variations in expansion and contraction of the parts in service.

Another and more specific object of the invention is to provide a floating head cover assembly having a minimum number of parts and a minimum amount of machining required to produce the assembly, and so that the construction is relatively inexpensive and will withstand the duty required.

A still more specific object of the invention is to provide a floating tube sheet and cover assembly in which the cover is secured by a continuous ring or annular member, which, in turn, is detachably keyed to the tube sheet by a plurality of flat, partially circular key members.

Further objects and advantages of the invention will appear from the following description of a preferred form of embodiment thereof, taken in connection with the attached drawing, in which,

Fig. 1 is a substantially central vertical section through a part of a shell and tube type heat exchanger;

Fig. 2 is a partial horizontal section with parts broken away, taken substantially along the line 2—2 in Fig. 1;

Fig. 3 is a detailed vertical section through a modified form of securing device;

Fig. 4 is a view similar to Fig. 3 and showing a still further modified form of construction.

In accordance with the preferred form of em-

bodiment of my invention, the heat exchanger shell 10, which is sealed at one end, by the cover 12, is provided with a tube bank 14 with one end of the tubes fixedly secured to shell 10 in any well-known manner, as by a fixed tube sheet (not shown). The other end of the tube bank 14 is provided with floating tube sheet 16 so that the tube bank may expand and contract in a suitable manner. The floating tube sheet 16 is normally of slightly smaller diameter than the interior of 10 the shell 10 so that the tube bundle 14 may be removed.

As is also well-known, the floating tube sheet 16 is necessarily provided with a tube sheet cover 18 which acts as a channel for the transfer of 15 fluids from one part of the tube bank to the other. In accordance with my invention, the floating tube sheet cover 18 has a rim 19 to engage the gasket 20 which directly rests on the margin of the floating tube sheet 16. Preferably, 20 the floating tube sheet cover 18 is of the same diameter as the floating tube sheet 16.

The securing means to hold the cover to the tube sheet, which is the substance of my invention, includes a continuous annular ring 22 which 25 is provided with a depending portion 24 which surrounds the rim 19 on the floating tube sheet cover 18 and also surrounds the floating tube sheet 16. The lower portion of this depending portion 24 is conveniently anchored to the floating tube sheet 16 as by a plurality of key-like members 26. These key-like members are similar to the well-known Woodruff keys in that they are relatively flat members, partially circular, and may be projected through the wall of the depending portion 24 into the tube sheet 16.

As shown in Fig. 2, the tube sheet 16 may be conveniently provided with a continuous groove 28 to receive the keys 26, it being understood that the keys are placed in shear along the dotted line portion 29. The extent of the shear section can, of course, be varied to suit the desired operating conditions.

The openings for the keys 26 are conveniently made by automatic machinery, and close fits can be obtained. Furthermore, there is no tendency of the keys to move outward and a very secure connection can be made. With the continuous groove 28, there is no need to index the depending portion 24 with the tube sheet, although, of course, if indexing were desirable, it would be relatively easy to form the key slots in the depending portion 24 and in the tube sheet 16 simultaneously.

The annular member 22 is also provided with 55

an overhanging flange portion 30 to receive adjustable screw members 32, which co-act with the boss portion 34 on the floating tube sheet cover 18. From inspection of Fig. 1, it will be 5 apparent that the tube sheet cover 18 is held tight against removal by the bolts 32 with a direct reaction on the tube sheet 16. Removal of the cover 18 is accomplished when shell cover 12 is removed by merely loosening the bolts 32. The keys 26 10 can then be quickly removed by tapping on one edge and thereafter the annular member 22 and the cover member 18 can be removed.

The construction described is very economical, as it merely requires that the tube sheet and 15 cover be turned to a common diameter with the tube sheet suitably grooved intermediate its top and bottom edges. The annular member 22 is also a relatively simple element, which is slotted at spaced intervals to receive the desired number 20 of keys. The apparatus can be assembled and disassembled by unskilled labor and can be made extremely tight and will withhold high pressures, irrespective of diameter changes, it being noted that the screws 32 are in compression, with the 25 result that there is no material change in expansion between the inner and outer portions consisting, respectively, of the depending part 24 of the annular ring 22 and the boss portion 34 of the cover 18.

30 The modified form of construction shown in Fig. 3, in which the floating tube sheet is indicated at 40, is adapted to have the same type of tubes forming the tube bank 14, and is provided with a similar type of cover 18 which is secured 35 thereto by the annular member 22 through the adjustable bolts 32. The keys 26 are also of the type shown in Fig. 2, but in this construction the keys 26 enter into a hardened ring member 42, which is recessed into the tube sheet 40.

40 Under some circumstances, the tube sheet 40 may be of such a material, such as bronze, that the unit stresses are so great that the keys 26 would cause a deflection within the tube sheet. In such case, the use of a hardened supplementary ring member, such as 42, which can be recessed within the tube sheet, offers an effective 45 connection.

A further alternative construction is shown in 50 Fig. 4, in which the cover 18 is secured to the tube sheet 16 by an annular ring 45 and held by the adjustable bolts 32 in a manner similar to the construction shown in Fig. 1. In this case, however, the depending portion 46 of the annular 55 member 45 is somewhat greater in extent than the same construction as shown in Fig. 1, and the keys 26, which are projected through the wall thereof, extend below the bottom of the tube sheet 16. This is particularly advantageous in 60 case of very thin tube sheets where it may be

found undesirable to form the groove 28 as shown in Fig. 1.

While I have shown preferred forms of embodiment of my invention, I am aware that modifications may be made therein and I, therefore, desire a broad interpretation of my invention herein in the scope and spirit of the disclosures herein and of the claims appended hereinafter.

I claim:

1. In a heat exchanger of the class described 10 having a shell, a tube bundle therein, including a tube sheet fixed to the shell, and a floating tube sheet removable through said shell, the combination of a cover for said tube sheet and means to secure said cover to said tube sheet, said means 15 comprising a continuous ring member surrounding the periphery of the cover and tube sheet, multiple anchoring means engaging both the continuous ring member and the tube sheet to anchor the ring member against movement with respect 20 to the tube sheet, and adjustable members engaging the cover and reacting through the ring member whereby on adjustment the cover may be forced against the tube sheet, said anchoring means being a series of projecting keys having 25 a semi-circular contour and projecting through the wall of the continuous ring member so as to be rotatable from the exterior, the space between the keys being approximately equal to the width 30 of the keys.

2. In a heat exchanger of the class described having a shell, a tube bundle therein including a tube sheet fixed to the shell and a floating tube sheet removable through said shell, the combination of a cover for said tube sheet and means to 35 secure said cover to said tube sheet, said means comprising a continuous ring member of inverted L-shape in cross section, one flange of which overlies the cover, adjustable members carried by said flange and adapted to engage the cover, the 40 other portion of said continuous ring member being substantially cylindrical and overlying the peripheries of the cover and the tube sheet, and a plurality of key members projecting through the wall of said continuous ring member and projecting beyond the outer diameter of said tube sheet, said projecting keys being retained in operative position by a part of the heat exchanger shell.

3. In a heat exchanger of the class described 50 in claim 2, the projecting keys being flat and constituting an anchoring surface of substantial extent, against which said tube sheet reacts.

4. In a heat exchanger of the class described 55 in claim 2, the tube sheet being recessed on the surface opposite that which the cover engages and being provided with a supplemental ring, such supplemental ring being recessed to receive the projecting keys.

JOHN A. GIBB. 60
